LOAD EQUALIZER FOR DEEP WELL PUMPS

Oliver D. Le Blanc, Trees, La.

Application October 28, 1935, Serial No. 47,175

2 Claims. (Cl. 103—223)

This invention relates to a load equalizer for deep well pumps, and has for the primary object the provision of a device of this character which will minimize vibration to deep well pumps and thereby reduce wear to the pump parts and the well tubing and reduce to a minimum repairs and the pulling of sucker rods and labor costs incident thereto and which will permit pumps to be operated at a higher rate of speed to increase the pump output.

With these and other objects in view, this invention consists in certain novel features of construction, combination and arrangement of parts to be hereinafter more fully described and claimed.

For a complete understand of my invention, reference is to be had to the following description and accompanying drawing, in which

Figure 1 is a vertical sectional view illustrating a load equalizer for deep well pumps showing the same adapted to a well tubing.

Figure 2 is a top plan view, partly in section, showing the equalizer.

Figure 3 is a fragmentary sectional view showing the valve of the equalizer.

Figure 4 is a detail sectional view taken on the line 4—4 of Figure 3.

Referring in detail to the drawing, the numeral 1 indicates in entirety a load equalizer unit adapted to be connected between sections of the pump tubing 2. The unit 1 consists of a casing 3 having upper and lower necks 4 and 5. The upper neck 4 is internally screw threaded to receive the screw threaded end of one of the sections of the well tubing and also the upper end of a tube 6, the latter extending downwardly through the casing 3 into the neck 5. The tube 6 forms a continuation of the well tubing through the casing 3 and provides in the latter an equalizing chamber 7.

The neck 5 consists of a coupling 8 equipped with packing 9 and to which is threaded the lower end of the tube 6. The coupling 8 connects to another section of the well tubing. The sucker rod 10 if the pump (not shown) extends through the well tubing and the tube 6. The sucker rod is of a conventional construction and is reciprocated to elevate liquid upwardly through the tubing.

The casing 3 includes sections detachably connected by screw threads, as shown at 10, and slidably mounted in the chamber 7 of said casing is a float 11 equipped at opposite ends with cups 12 which frictionally contact the walls of the casing. The float 11 separates the upper portion of the

chamber 7 from the lower portion. The cups 12 besides contacting the casing also contact the tube 6. The purpose of the float 11 and the cups 12 thereof is to separate an air column from a liquid column in the casing or the chamber 7 thereof. The air column is located in the upper portion of the casing and acts to absorb shocks due to the column of liquid being lifted by the upward movement of the sucker rod. A port 13 is formed in the tube 6 below the float 11 and associated therewith is a flap valve 14, pivotally mounted, as shown at 15. The flap valve opens outwardly in the chamber 7 from the tube 6. However, when moved in an opposite direction will close the port 13 and has a rib 16 which projects into the tube 6 when the flap valve is in the last-named position or in the position of closing the port 13. The rib 16 is disposed vertically and tapers towards its upper end.

Fittings 17 and 18 are provided in the top wall of the casing and have therein outwardly seating check valves 19 which act to trap air in the chamber 7. The fitting 18 is employed for connecting a pipe of a compressor to the chamber 7 while the fitting 17 is employed for connecting a pressure gauge to the chamber 7. The pressure gauge is not shown and forms no part of the present invention and is only employed when desiring to ascertain the air pressure in the chamber 7 and is of a type when fitted in the chamber 7 will unseat the valve 19 thereof to place the gauge in communication with the chamber 7.

The float 11 has a removable plug 20 so that shot or small weights may be placed in the float 11 when desiring to increase the weight of said float.

The device described is especially adaptable for pumps employed in deep wells and the unit is installed between two sections of a well tubing and air is forced into the chamber 7 with the port 13 closed by the flap valve 14. The unit is lowered into the well with the well tubing having the sucker rod 10 of the pump extending therethrough. The air pressure is built up until it is equal to the load of the column of liquid in the well tubing above the unit. The upstroke of the sucker rod elevating the column of water below the unit will bring about vibration to the pump by said column of liquid contacting the column of liquid above the unit and to absorb this vibration the column of liquid elevated below the unit when contacting the column of liquid above the unit passes into the lower portion of the chamber 7 by way of the port 13 and compresses the

column of air therein permitting the latter to absorb the shock. During the downstroke of the sucker rod the expansion of the air column forces liquid from the lower portion of the chamber 7 back through the port 13 and upwardly through the tube 6. Thus it will be seen that the column of air absorbs shock, thereby reduces vibration and acts as a load equalizer. The float between the column of air and the liquid prevents commingling thereof. The float 11 is movable with the liquid and the column of air and acts as a separator.

After the column of air has been built up to a desired pressure in the chamber 7 and the unit 15 is lowered into the well, the flap valve 14 may stick and not open the port 13 so the rib 16 is provided on the flap valve to be engaged by the sucker rod during the lowering of the latter or the usual cups on said sucker rod which will 20 unseat the flap valve and bring about opening of the port.

A device of the character described will reduce wear on well tubing as well as the parts of the pump by the reduction of vibration to a minimum 25 and also will relieve fatigue in sucker rods. By reducing wear on the pump and its parts it will also materially reduce the number of times that a pump must be disassembled in order to make repairs thereto.

30 By reducing the peak load on the pump and distributing it over a greater arc of the crank shaft of the pump it enables operating the pump at a high rate of speed thereby increasing the output of the pump.

35 Having described the invention, I claim:

1. A load equalizer for deep well pumps comprising a casing connecting sections of a well tubing, a tube located in said casing for connecting said sections of the well tubing for the passing of a column of liquid from one section of the well tubing to the other section of said well tubing, and having a port communicative with said casing, means for controlling said port, a flap valve for controlling said port, and means on said casing to permit connecting of an air supply 10 means to the space between said casing and the tube for developing therein an air column to act against a liquid column in said casing from the tube by way of said port, and a slidable separator in said casing separating the air column from the 15 liquid column.

2. A load equalizer for deep well pumps comprising a casing connecting sections of a well tubing, a tube located in said casing for connecting said sections of the well tubing for the passing 20 of a column of liquid from one section of the well tubing to the other section of said well tubing, and having a port communicative with said casing, means for controlling said port, a flap valve for controlling said port, means on said casing to 25 permit connecting of an air supply means to the space between said casing and the tube for developing therein an air column to act against a liquid column in said casing from the tube by way of said port, a slidable separator in said 30 casing separating the air column from the liquid, and means for varying the weight of said separator.
